FREDERICK W. BROCKSIEPER, OF NEW HAVEN, CONNECTICUT, ASSIGNOR TO SARGENT & CO., OF SAME PLACE.

Design No. 4,428, dated October 25, 1870.

DESIGN FOR A MATCH-SAFE.

The Schedule referred to in these Letters Patent and making part of the same.

To all whom it may concern:

Be it known that I, FREDERICK W. BROCKSIEPER, of New Haven, in the county of New Haven and State of Connecticut, have invented a new Design for Match-Safe; and I do hereby declare the following, when taken in connection with the accompanying photographic illustration to be a full, clear, and exact description of the same, and which illustration constitutes part of this specification, and represents a front view.

This invention relates to a design for match-receiver, and consists in the combination of ornamental parts, as fully shown in the accompanying photographic illustration.

The receiver represents a game-bag, by the strap of which the bag is suspended; upon one side hangs a bird, and upon the other a rabbit, all as fully shown in the accompanying photographic illustration.

I claim as my invention—

The design for match-receiver, as shown.

F. W. BROCKSIEPER.
